Application May 4, 1953, Serial No. 24,829

Term of patent 7 years

(Cl. D54—13)

To all whom it may concern:

Be it known, that I, Vincent J. Fabian, a citizen of the United States of America, residing at Annapolis, Maryland, have invented a new, original, and ornamental Design for a Fid Splicer, of which the following is a specification, reference being had to the accompanying drawings, forming part thereof.

Fig. 1 is a front view of a fid splicer showing my new design. Fig. 2 is a side view of my fid splicer looking from the left of Fig. 1.

Fig. 3 is a cross-sectional view taken along lines 3—3 of Fig. 1.

Fig. 4 is a cross-sectional view taken along lines 4—4 of Fig. 1.

I claim:

The ornamental design for a fid splicer, as shown.
